UNITED STATES PATENT OFFICE.

JAMES H. DEAN, OF LUDINGTON, MICHIGAN, ASSIGNOR TO NORTHWESTERN EXPANDED METAL COMPANY, OF CHICAGO, ILLINOIS, A CORPORATION OF ILLINOIS.

SHEET-METAL LATH.

Application filed December 7, 1925. Serial No. 73,908.

The object of this invention is to form expanded metal lath having longitudinally extending ribs with groups of meshes preferably of rectangular form between the ribs, the meshes of each group being arranged in rows and the meshes of the rows, or of some thereof, varying in size as desired.

The invention consists generally in the lath hereinafter described and claimed and in the method or process of making the same.

In the accompanying drawings forming part of this specification:

Figure 1 is a plan view of a section of sheet metal showing the preferred manner of cutting the slits therein preparatory to forming the meshes in the lath;

Figure 2 is a plan view of a portion of the metal lath showing the preferred form and arrangement of the meshes therein, and also showing the longitudinal ribs between the groups of meshes; and

Figure 3 is a detail sectional view showing the lath mounted upon a wall and the plaster applied thereto.

In carrying out my invention I provide a sheet of metal 4 of the weight and thickness usual for making lath, and I cut therein groups of diagonally extending slits 8 and 9 having unslotted sections or portions 5 and 6 between said groups of slits (Figure 1). As here shown the unslotted portions 5 and 6 are bent to form longitudinally extending ribs 11 and 12, the ribs 11 formed from the wider unslotted portions 5 being deeper than the ribs 12 which are formed from the narrower unslotted portions 6.

After the sheet is slotted it is expanded and the sheet is thereby provided with the longitudinal rows of rectangular meshes, the meshes of each row being all of the same size, but differing in size from the meshes of the other rows, or some thereof.

An important feature of this invention resides in the novel method of arranging the slits that form the meshes 14, 15 and 16 between the respective ribs 11 and 12. Referring to Figure 2 it will be noted that the meshes here shown are substantially square in form, and that the meshes in each row are of uniform size, but that the meshes in the adjacent rows are of a different size. It will be noted that the strands 17, bonding strips 18, and the ribs 11 and 12, which define the meshes 14, 15 and 16, are arranged at right angles to one another, thereby con-

structing a lath having a plurality of vertically and horizontally arranged members. The purpose of constructing the lath with groups of meshes in which the meshes in each row of a given group are of a different size than the meshes in adjacent rows, is to effect a saving in the amount of plaster required to cover the lath, in that only a small portion of the plaster will be forced through the relatively small meshes 15 and 16, while a greater portion will be forced through the larger meshes 14 to provide an anchor or key to hold the plaster in place.

The groups of diagonally extending slits cut in the sheet metal blank between the spaces 5 and 6 from which the ribs 11 and 12 are formed, are preferably arranged as shown in Figure 1. As here shown, three rows of slits are provided between each pair of unslotted portions of the blank. The slits 19, which are relatively longer, are arranged in parallel relation with one another, and shorter slits 21, in the intermediate row of each group, are also arranged in parallel relation with one another but at a slightly different angle with relation to the slits 19. The slits 22, shorter than the slits 21, are likewise parallel with the other slits in the same group and are arranged at a different angle relative to the slits 19 and 21 in the other rows. In cutting the slits 19, 21 and 22 in the blank, the strands 17 are preferably of uniform width, and the bonding strips 18 are likewise of a uniform width so that when the sheet is expanded as shown in Figure 2, the strands 17 will all be of uniform width as will also be the bonding strips 18.

The sizes of the meshes are determined by the lengths of the slits 19, 21 and 22. I usually arrange the largest meshes on opposite sides of the larger ribs 11, whereby the larger amount of plaster will pass through the lath near these ribs and thereby firmly lock the plaster sheet to the lath contiguous to the lines of fastening of the lath to the wall.

In the drawings I have shown a metal lath comprising three rows of meshes between adjacent ribs, and the meshes of each row varying in size from the meshes of adjacent rows. The meshes may also vary in arrangement from that shown in Figure 2, as for instance, the outer rows of meshes 14 may be of the same size as the inner rows of meshes 16,

or if desired, the intermediate rows of meshes 15 may be larger than the meshes 14 and 16 in the adjacent rows. The larger ribs 11 are of sufficient size to receive the 5 nails 23 for securing the lath to the building wall as shown in Figure 3.

It is, therefore, possible by this method, to produce lath with any desired variation in the sizes of the meshes of the different 10 rows.

I do not wish, however, to confine the invention to this particular construction, as any suitable number of rows of meshes may be provided between the ribs without departing 15 from the invention.

I claim as my invention:

1. As a new article of manufacture, an expanded metal sheet provided with rows of meshes, the meshes of any row being all of 20 the same size but differing in size from those of the other rows.

2. As a new article of manufacture, an expanded metal sheet provided with unslotted

parallel sections with rows of meshes between said sections, the meshes of any row 25 being of the same size but differing from those of other rows.

3. As a new article of manufacture, an expanded metal sheet provided with unslotted parallel sections having ribs formed in said 30 sections with rows of meshes between said sections, the meshes of any row being of the same size but differing from those of other rows.

4. As a new article of manufacture, an expanded metal sheet provided with unslotted parallel sections having ribs formed therein, and with rows of meshes between said sections, the meshes of any row being of the same size but differing from those of other 40 rows and the larger meshes being adjacent unslotted portions of the sheet.

In witness whereof, I have hereunto set my hand this 27th day of October, 1925.

JAMES H. DEAN.
